US00D533460S

(12) **United States Design Patent** (10) **Patent No.:** **US D533,460 S**
Terrasi (45) **Date of Patent:** **** Dec. 12, 2006**

(54) **PACKAGING FOR FOOD PRODUCTS**

(75) Inventor: **Giuseppe Terrasi**, Benevello (IT)

(73) Assignee: **Soremartec S.A.**, Schoppach-Arlon (BE)

(**) Term: **14 Years**

(21) Appl. No.: **29/214,638**

(22) Filed: **Oct. 7, 2004**

(30) **Foreign Application Priority Data**

Apr. 8, 2004 (EM) 000163928

(51) **LOC (8) Cl.** **09-01**

(52) **U.S. Cl.** **D9/600; D9/418**

(58) **Field of Classification Search** D3/270-271.1, D3/273; D7/602, 604, 613, 628; D9/600, D9/669, 414, 418, 420-426; 215/400; 220/890; 206/457, 822, 830; D21/386-390

See application file for complete search history.

It is certified that error appears in the above-identified patent and that said Letters Patent is hereby corrected as shown below:

Attached please find Replacement Formal Drawings to correct the informal drawings that are included in the Letters Patent.

The title page should be deleted and substitute therefor the attached title page.

Drawings:

Delete drawing sheets 1-2, and substitute therefor the drawing sheets, consisting of Figs. 1-7 as shown on the attached pages

Signed and Sealed this

Twenty-seventh Day of March, 2007

A handwritten signature in black ink, appearing to read "Jon W. Dudas". The signature is written in a cursive style with a large, stylized "J" at the beginning.

JON W. DUDAS
Director of the United States Patent and Trademark Office
